(57) **CLAIM**

The ornamental design for a combined light and speaker, as shown and described.

DESCRIPTION

FIG. 1 is a front, bottom, right perspective view of a combined light and speaker showing our new design; FIG. 2 is a front, top, right perspective view thereof; FIG. 3 is a front elevational view thereof; FIG. 4 is a rear elevational view thereof; FIG. 5 is a left side elevational view thereof; and, FIG. 6 is a right side elevational view thereof. The broken lines showing of parts of the combined light and speaker form no part of the claimed design. The dot-dash broken lines show boundaries of the claimed design and form no part of the claimed design.
